DIGITAL CLOCK RADIO

Katsuhiro Makino, Hirakata-shi, Toshimasa Akazawa,
Yao-shi, and Keizo Kushida, Osaka-shi, Japan, assignors
to Matsushita Electric Industrial Co., Ltd., Kadoma-
shi, Osaka, Japan

Filed Dec. 18, 1974, Ser. No. 534,124

Claims priority, application Japan July 19, 1974

Term of patent 14 years

Int. Cl. D10—01

U.S. Cl. D56—4 B

FIG. 1

FIG. 2

FIG. 1 is a front, top and right side perspective view of a digital clock radio showing our new design; and

FIG. 2 is a rear, bottom and left side perspective view thereof.

The larger rectangular aperture behind the face plate is symmetrical and centrally located within the face plate opening.

We claim:

The ornamental design for a digital clock radio, as shown.
